UNITED STATES PATENT OFFICE.

JACOB W. SHULL, OF SPRINGCHURCH, PENNSYLVANIA.

BURIAL APPLIANCE.

No. 806,998.

Specification of Letters Patent.

Patented Dec. 12, 1905.

Application filed March 18, 1905. Serial No. 250,705.

To all whom it may concern:

Be it known that I, JACOB W. SHULL, residing at Springchurch, in the county of Armstrong and State of Pennsylvania, have invented a new and Improved Burial Appliance, of which the following is a specification.

This invention, which generally relates to burial appliances, is in the nature of an improved shipping or casket-receiving box, and 10 it seeks to provide a box of this character equipped with means for covering or lining the walls of the grave, so as to remove so far as possible the sight of the earthen sides and ends of the grave during the operation of 15 lowering the casket containing the body into the grave.

With the above and other objects in view, which will hereinafter appear, my invention comprehends a means attachable to the ordinary casket-receiving box adapted to be adjusted to cover the sides and ends with a neatly-looking but cheap lining that can be quickly fitted over the walls of the grave and after the coffin has been lowered can be folded over the coffin under the top or lid of the receiving-box.

In its more subordinate features my invention embodies side and end frames of a light and flexible material attached to the upper 30 edge of the casket-receiving box, extensible, so as to positively cover the corners of the grave, and which when the coffin has been lowered will fold down upon each other and within the box, certain details of construction 35 and combination of parts being also embodied in my invention, all of which will be hereinafter fully described, pointed out in the appended claims, and illustrated in the accompanying drawings, in which—

40 Figure 1 is a perspective of a burial-box equipped with my improvements, part of the lid being broken away to show the location of the lining members. Fig. 2 is a view of a grave, showing the flexible attachments elevated to line the walls of the grave. Fig. 3 is a longitudinal section of the same, taken practically on the line 3 3 of Fig. 2. Fig. 4 is a cross-section thereof on the line 4 4 of Fig. 1. Fig. 5 is a detail perspective view 45 illustrating a modified arrangement of the lining members, the same being shown composed of light wires having extensible ends.

In the simplest, cheapest, and preferred form my invention comprises a pair of side 50 members $a a'$ and a pair of end members $b b'$,

the side members being of the full length of the box B between its ends $B' B'$ and the end members $b b'$ being of the full width of the said box, and the side members have a height equal or slightly less than that of the width 60 of the box B, so that when folded down as shown in Fig. 4 the said side members $a a'$ will fit between the sides of the box B, and the ends $b b'$ are of a height sufficient when raised as shown in Fig. 2 to extend up to the top of 65 the grave. To provide for completely covering the sides of the grave to the top, the side members $a a'$ are provided with supplemental sections a^2 , hinged to the outer edge of said members $a a'$ by a flexible strip 2^a to fold 70 back over the said members $a a'$ when the parts are down under the lid B², as best shown in Fig. 4, by reference to which it will be seen the lid B² may be hinged to the top of the box B. 75

The inner face of the side and end members $a a'$ and $b b'$, as also the supplemental side sections a^2 , are covered on their inner face with a lace or other neat fabric C, preferably similar to the lining of an ordinary casket, and 80 the said fabric C is made of sufficient fullness to fold or lap plait-like, the purpose of which I will now explain.

In cutting the grave-opening the same is longer and wider than the rough receiving-box to permit of freely lowering it to the bottom of the grave. To provide for completely covering the walls of the grave with the lining, I form at the extreme ends of the side members extensible sections 10 and 10^a, which 90 are joined to the side members by the fabric facing C, and by reason of the fullness of said facing the ends 10 and 10^a when the members a and a' are swung out of the box B can be extended to fit close up into the corners of 95 the grave, as clearly shown in the drawings, to which position the said ends 10 10^a until the coffin has been lowered are held by pins or pegs D, driven through the said ends 10 10^a into the walls of the grave. The end members $b b'$ are likewise extensible laterally, and for such purpose they are split their full height and also connected by the facing fabric, which for the said ends $b b'$ also has sufficient fullness to provide for folds or plaits 100 when the sections that compose the ends $b b'$ contract. To draw the two members that form the ends $b b'$ normally together, so that the said ends $b b'$ will readily fold down into the box, elastic cords F are attached to the 110

back of the upper edges thereof, similar cords E being attached to the side members a a' and their supplemental sections, as shown. The side and end members a a' and b b' , which are 5 preferably composed of cardboard, thin veneer, and the like, are hinged to the upper edge of the box B by the flexible hinge portions G, as shown.

From the foregoing, taken in connection 10 with the drawings, the complete structure of the simplest and cheapest form of my invention will be readily apparent.

The box is lowered into the grave as usual, the lid of the box B then opened in the usual 15 manner, and one of the side members a is then swung up or unfolded, its ends extended to snugly fit up into the corner of the grave, and the said member a made fast to its position by the pegs or nails D. The end 20 members b b' are then likewise swung up, adjusted, and made fast, and then the other side member a' is fixed in position, thus completely lining the side walls of the grave and effecting a neat and presentable grave, ready to receive 25 the casket. After the casket is lowered the side a is folded down on the top of the casket, then the ends, and then the other side a' , the supplemental upper sections of the sides being folded back, after which the lid B^2 is 30 closed and the grave left ready for filling.

Instead of using cardboard, thin veneer, and the like, as stated, for the side and end members they may be formed of light flexible wire members, arranged as shown in Fig. 5, 35 in which the ends a^5 have a hinged connection with the inside of the box B and the upper portions 5^a are connected to the cross-bar a^6 , the two portions a^5 and a^6 being formed integrally with each other and of springy material to normally assume such a position that 40 under normal conditions the frame will swing down into the box B, it being understood that when the modified form of my invention is used the end members thereof are likewise 45 formed of flexible wire sections and the fab-

ric or lining material is stitched or otherwise made fast to the said wire frames.

Having thus described my invention, what I claim, and desire to secure by Letters Patent, is—

1. A burial appliance comprising a casket-receptacle, a box and means carried thereon foldable within the said box and extensible from the sides and ends of the box to form a lining for the walls of the grave. 50

2. An attachment for burial-boxes, consisting of a frame adapted to be hinged to the upper edge of the box to fold therein, said frame having a covering and adapted to be swung up over the wall of the grave to form 60 a lining therefor.

3. An attachment for burial-boxes, which comprises a frame adapted to be hinged to the box to fold therein and to be swung up against the side of the grave, said frame having extensible end portions, and a fabric covering for the said frame. 65

4. An attachment for burial-boxes which comprises a flexible frame hinged to the box to fold therein and to swing up against the 70 wall of the grave, said frame having extensible end portions, means for drawing the ends inwardly, a fabric loosely mounted on the frame for the purposes described.

5. In combination with the box B, the side 75 and end frames formed of a flexible material hinged at their lower end to the inner side of the upper edges of the box, said frames having extensible end sections, spring devices 80 for drawing the end sections normally inward and a flexible body wholly covering the said frames, and having sufficient fullness to permit of drawing out the end portions of the said end and side members for the purposes specified.

JACOB W. SHULL.
